US00D969552S

(12) **United States Design Patent** (10) **Patent No.:** **US D969,552 S**
McConnell et al. (45) **Date of Patent:** **** Nov. 15, 2022**

(54) **NOZZLE FOR A STAND MIXER GRINDER ATTACHMENT**

(71) Applicant: **WHIRLPOOL CORPORATION**,
Benton Harbor, MI (US)

(72) Inventors: **John W. McConnell**, St. Joseph, MI
(US); **Nicholas Schutte**, St. Joseph, MI
(US); **Anne Wessel**, St. Joseph, MI
(US)

(73) Assignee: **Whirlpool Corporation**, Benton
Harbor, MI (US)

(**) Term: **15 Years**

(21) Appl. No.: **29/816,382**

(22) Filed: **Nov. 22, 2021**

(57)

CLAIM

The ornamental design for a nozzle for a stand mixer grinder attachment, as shown.

DESCRIPTION

FIG. 1 is a front-perspective view of a nozzle for a stand mixer grinder attachment according to the design;
FIG. 2 is a front elevation view thereof, back, left, and right elevation views being identical thereto;
FIG. 3 is a top plan view thereof; and,
FIG. 4 is a bottom plan view thereof.

1 Claim, 3 Drawing Sheets
